UNITED STATES PATENT OFFICE.

THOMAS C. SHEEHAN, OF NEW YORK, N. Y., ASSIGNOR TO THE TRINITY PRESS COMPANY, A CORPORATION OF NEW YORK.

BLANKET FOR LITHOGRAPHIC AND OTHER PRESSES.

No. 839,214.

Specification of Letters Patent.

Patented Dec. 25, 1906.

Application filed March 17, 1906. Serial No. 306,642.

To all whom it may concern:

Be it known that I, THOMAS C. SHEEHAN, a citizen of the United States of America, residing at New York, in the county of New York and State of New York, have invented certain new and useful Improvements in Blankets for Lithographic and other Presses, of which the following is a specification, such as will enable those skilled in the art to 5 to which it appertains to make and use the same.

The object of this invention is to provide a new and improved blanket for lithographic or other printing presses which may be 15 tightly drawn about a cylinder of said press without danger of tearing said blanket, a further object being to provide a blanket of this type which may be used either in two-cylinder presses as a base or platen for printing or 20 in three-cylinder presses as a transferring medium, and which when so used will not ride, wrinkle, or warp in the operation of said press.

My invention is fully described in the following specification, of which the accompanying drawings form a part, in which the separate parts thereof are indicated by suitable reference characters in each of the views, and in which—

30 Figure 1 is an edge view of a blanket of the class described, partially in section; and Fig. 2 is a plan view thereof, also partially in section.

In the drawings forming part of this specification I have shown a blanket *a*, composed of rubber or other similar resilient material, which is adapted to be wrapped about the cylinder of a lithographic or other press, and in the formation of my blanket I provide an 35 interlacing *b*, of wire-cloth, expanded metal, 40 perforated metal, or other flexible non-ten-

sile material, and this metal is preferably embedded in the blanket *a*, as clearly shown in the drawings; but the said blanket may be formed thereon in any desired manner.

45

In placing blankets of this type upon the cylinders of presses various kinds and classes of hooks and clamps are employed, and it will be obvious that I may adapt the metal 50 strengthener *b* of my blanket to suit any requirements; but in the drawings I have shown the said metal forming-loops *c*, by means of which the said blanket may be secured; but this forms no part of my invention, the basis thereof being the connection 55 with a rubber or other flexible blanket for lithographic presses of a non-stretching flexible-metal formation, and various changes in and modifications of the construction shown and described may be made to accomplish 60 the desired results without departing from the spirit of this invention or sacrificing its advantages.

55

Having fully described my invention, what I claim as new, and desire to secure by Letters Patent, is—

A blanket for lithographic and other presses, comprising a rubber or other resilient body, a wire passed across said body from side to side at intervals and a supplemental wire passed across said body from 70 end to end at intervals, the turns of said last-named wire extending beyond said body and forming attaching-loops.

75

In testimony that I claim the foregoing as my invention I have signed my name, in presence of the subscribing witnesses, this 15th day of March, 1906.

THOMAS C. SHEEHAN.
